US0D1023799S

(12) **United States Design Patent** (10) Patent No.: **US D1,023,799 S**
(45) Date of Patent: ** Apr. 23, 2024

(54) **THERMOMETER**

(71) Applicant: **Miao Xie**, Lianjiang (CN)

(72) Inventor: **Miao Xie**, Lianjiang (CN)

(**) Term: **15 Years**

(21) Appl. No.: **29/849,589**

(22) Filed: **Aug. 12, 2022**

(30) **Foreign Application Priority Data**

Jul. 27, 2022 (CN) 202230484506.X

(57) **CLAIM**

The ornamental design for a thermometer, as shown and described.

DESCRIPTION

FIG. 1 is a first perspective view of a thermometer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

(Continued)

The broken lines shown in the drawings depict portions of the thermometer in which the design is embodied that form no part of the claimed design.

1 Claim, 8 Drawing Sheets
